UNITED STATES PATENT OFFICE

2,046,479

BOTTOM HOLE TUBING ANCHOR

William O. Patterson, Oklahoma City, Okla.

Application September 6, 1935, Serial No. 39,382

9 Claims. (Cl. 103—202)

My invention relates to an anchor for rigidly, yet removably, positioning the lower end of well production tubing, and more particularly to production tubing used in connection with reciprocating pumps driven by pump-rods or "sucker-rods".

According to present practice, a pump-barrel is attached at its upper end to the lower end of a string of production tubing and lowered into the well to a point below the normal fluid level therein, or into the producing stratum. The pump-barrel has an intake for fluid in its lower end and contains a reciprocatable piston which is actuated by a string of sucker-rods leading to the earth's surface within the production tubing.

The outside diameter of the production tubing is invariably considerably less than the inside diameter of the well or its casing. Since the tubing is suspended in the well at the earth's surface in order to locate the intake aperture of the pump at a point above the bottom of the well, the pump is free to move bodily about within the confines of the well casing, or, if it is located in the well cavity in the production stratum below the casing, it is free to move about in the cavity which is invariably of greater diameter than that of the well.

When the pump is in operation, vertical movement of the sucker-rods and the surge of the production fluid, which in deep wells is under extremely high pressure, causes constant movement of the pump-barrel either laterally, rotatively, or a combination of both. This movement not only fatigues the production tubing and sucker-rod, wears out through frictional contact the sucker-rods, production tubing, well casing, and pump barrel, but in cases where the lower end of the barrel is within the production stratum, it agitates the producing sand and causes it to be produced with the production fluid.

The prime object of the present invention is to limit sharply lateral movement of the pump-barrel and to eliminate its accompanying deficiencies.

Other objects of the invention are to provide a device of the class described which is new, novel, practical and of utility; which will cause the production fluid to travel a devious path before entering the pump intake, thereby causing it to lose by gravitational stratification, much of its entrained sand or other foreign particles; which includes a removable pump-anchor the interior of which acts as a sand-trap for collecting such detritus; which includes a replaceable jacket closely surrounding the pump-barrel;

which, while anchoring the pump-barrel, permits the production tubing and pump-barrel to be suspended at the earth's surface in the usual manner, thus preventing the tendency to buckle or bend the production tubing which would be present if the barrel was supported upon the well bottom and in turn supported the weight of the tubing thereabove; which is simple in construction, operation, and installation; which is durable; and, which will be efficient in accomplishing all the purposes for which it is intended.

With these and other objects in view as will more fully appear hereinbelow, my invention consists in the construction, novel features, and combination of parts hereinafter more fully described, pointed out in the claims hereto appended, and illustrated in the accompanying one-sheet drawing, of which,

The figure is a fragmentary vertical sectional view of the lower portion of a cased well showing the device operatively installed therein, parts being shown broken away and parts being shown in vertical section.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawing is to be interpreted as being illustrative and not restrictive.

The inventive idea involved is capable of receiving a variety of mechanical expressions one of which, for the purpose of illustrating the invention, is shown in the accompanying drawing wherein:—

The reference numeral 1 indicates the lower section of a string of usual well casing supported at the bottom of a well 2 by concrete 3 in a usual manner. The production stratum or sand is indicated by the reference numeral 4 and the numeral 5 indicates the usual cavity in the stratum at the bottom of the well. The reference numeral 6 indicates the lower section of a string of usual production tubing which extends upwardly to and is suitably supported at the earth's surface. A string 7 of usual sucker-rod extends downwardly within the tubing string 6 from the earth's surface and is driven to reciprocal movement by power equipment, not shown. The lower end of the sucker-rod string 7 is attached to and acts to reciprocate a suit-

able pump-piston, not shown, which is operatively confined within a suitable pump-barrel 8. The elements described above with relation to the reference numerals 1 to 8 inclusive are usual except that the pump-barrel 8, instead of terminating with a plain lower end, is provided with exterior threads 9.

In my device I employ a collar 20 for connecting the lower end of the tubing 6 to the upper end of a smooth surfaced nipple 21 to the lower end of which is connected by a coupling 22 the upper end of the pump-barrel 8. To the threads 9 at the lower end of the pump-barrel 8 is connected by a coupling 23 the upper end of a depending extension tube 24 which has an open lower intake end.

Around the nipple 21 is provided a centrally bored exteriorly threaded head 25 through which the sleeve 21 is free to slide. The adjacent ends 20 of the couplings 20 and 22 act to limit the upward and downward movement of the sleeve 21 within the head 25.

Threadedly connected to the head 25 is a tubular jacket 26 to the lower end of which is connected by a coupling 27 the upper end of a tubular anchor 28 having a lower closed end 29. An annular space 30 is thus formed around the extension tube 24 and within the anchor 28. At a desired distance above the bottom end of the tube 24, the anchor 28 is provided with a plurality of inlet perforations 31 for production fluid, and the lower closed end 29 of the anchor occurs at a considerable distance below the lower end of the tube 24. The space within the anchor 35 below the lower end of the tube 24 acts as a sand-trap for receiving any detritus which may settle therein from the production fluid.

In operation, the complete device including the pump is lowered into the well by the production tubing 6 until the anchor 28 is imbedded in the sand at the bottom. During the lowering operation, the anchor 28, the jacket 26 and the head 25 are supported upon the upper end of the coupling 22. After the anchor is set upon the well bottom, the tubing is lowered sufficiently to leave the weight of the anchor supported entirely by the bottom of the well where it remains stationary during operation of the pump. The tubing is then hung at the earth's surface in a usual manner.

If desired, the lower end of the anchor 28 may be made more or less pointed so that it may be driven into the well bottom by using the tubing string 6 and the coupling 20 as a set of jars, similarly to the usual operation of drill-stem jars.

When in place, production fluid must pass through the perforations 31, downwardly in the annular space 30, and upwardly through the extension tube 24, before it can enter the pump-barrel 8. Since the fluid must change direction of flow before entering the lower end of the tube 24, detritus entrained therein has a tendency to settle into the bottom of the anchor 28 from which it may be periodically removed by pulling the equipment from the well.

It will be understood, of course, that the end 29 of the anchor 28 may be located at any desired distance below the bottom of the tube 24; that the lower end of the tube 24 may be located at any desired distance below the perforations 31; or that desired results might be obtained by eliminating the tube 24 and placing the perforations 31 in the jacket 26 at a point above the lower or intake end of the pump-barrel 8 instead

of placing them in the anchor 28 as illustrated. Also, that suitable results could be obtained by providing suitable shoulders around the upper portion of a pump barrel in lieu of the collar 20 and coupling 22, and the head 25 could then surround the barrel instead of the nipple 21.

It will, of course, be understood that the perforations 31 must be located below the normal fluid level in the well, whether that level occurs within the stratum 4 or thereabove in the casing 10 1. The reference numeral 32 indicates an imaginary fluid level.

It is not absolutely imperative that the perforations 31 in the jacket be located below the pump-intake since the anchor 28 when resting 15 upon or imbedded in the bottom of the well will remain stationary and will thus prevent agitation of the well fluid by movement of the pump-barrel. However, if the perforations 31 were located below the pump-intake, the well fluid would not be 20 forced to alter its direction when entering the pump, and consequently the benefits derived therefrom would be partially lost.

Obviously, the invention is susceptible of embodiment in forms other than that which is illustrated in the accompanying drawing and described herein, and applicable for uses and purposes other than as detailed, and I therefore consider as my own all such modifications and adaptations and other uses of the form of the 30 device herein described as fairly fall within the scope of my invention.

Having thus described my invention, what is claimed and desired to be secured by Letters Patent, is:

1. In a pump anchor for reciprocating well pumps, the combination with a string of production tubing and a pump barrel supported thereby within a well, of a jacket surrounding the barrel and having a closed lower end, inlets for fluid carried by the jacket and located above the intake of the pump, and means above the barrel for slidably connecting the jacket to the tubing.

2. Organization as described in claim 1, and means for limiting movement of the jacket with relation to the barrel.

3. In a pump anchor for reciprocating well pumps, the combination with a reciprocating pump having an intake and being supported in the well by a string of production tubing, of a jacket surrounding the barrel of the pump in a manner permitting its longitudinal movement with relation to the barrel, a closure for the lower end of the jacket, inlets for well fluid through the wall of jacket above the pump intake, and means for limiting relative movement of the pump-barrel and the jacket.

4. Organization as described in claim 3, in which the portion of the jacket lying between the pump-intake and the closure acts as a sand-trap.

5. Organization as described in claim 3, in which the portion of the jacket lying between the pump-intake and the closure acts as a sand-trap and is removable from the remainder of the jacket.

6. In pump apparatus, a string of production tubing adapted to be suspended in a well, a pump-barrel for a reciprocating pump supported by the lower end of the string and having an intake for well fluid, a jacket surrounding the barrel and having its upper end slidably supported with relation to the barrel, means for limiting relative movement of the jacket and barrel, a closure for the lower end of the jacket, and an inlet for well 75

fluid through the wall of the jacket above its closed end.

7. In a pump or bottom hole tubing anchor for reciprocating well pumps, the combination with a string of production tubing, of a pump-barrel, a jacket surrounding the barrel of the pump having a closed lower end for seating on the bottom of the well, inlets for fluid carried by the jacket and located above the intake of the pump, and means above the barrel for slidably connecting the jacket with relation to the barrel.

8. Organization as described in claim 7, and means for limiting movement of the jacket with relation to the barrel.

9. In a pump anchor for reciprocating well pumps, the combination with a reciprocating pump having an intake and being supported in the well by a string of production tubing, of a jacket surrounding the barrel of the pump in a manner permitting its longitudinal movement with relation to the barrel, a closure for the lower end of the jacket said closed jacket adapted to set on the bottom of the well, inlets for well fluid through the wall of jacket above the pump intake, and means for limiting relative movement of the pump-barrel and the jacket. 5 10
